Primary Examiner — Calvin E Vansant*Assistant Examiner* — Eidiol Ghigliotti Torres(74) *Attorney, Agent, or Firm* — Marshall & Melhorn, LLC(57) **CLAIM**

The ornamental design for a catalytic converter protection device as shown and described.

DESCRIPTION

FIG. 1 is a bottom perspective view of a catalytic converter protection device showing one embodiment of my new design;

FIG. 2 is a top perspective view thereof;

FIG. 3 is a front view thereof;

FIG. 4 is a rear view thereof;

FIG. 5 is a bottom plan view thereof;

FIG. 6 is a top plan view thereof;

FIG. 7 is a first side view thereof; and,

FIG. 8 is a second side view thereof.

The broken lines in the drawings are included to show portions of the catalytic converter protection device that form no part of the claimed design.

1 Claim, 3 Drawing Sheets(56)
